UNITED STATES PATENT OFFICE.

JOHN T. BROOKE, OF SEATTLE, WASHINGTON.

CREDIT-ACCOUNT APPARATUS.

972,154.

Specification of Letters Patent. Patented Oct. 11, 1910.

Application filed April 10, 1909. Serial No. 489,170.

To all whom it may concern:

Be it known that I, JOHN T. BROOKE, a citizen of the United States, residing at Seattle, in the county of King and State of

5 Washington, have invented certain new and useful Improvements in Credit-Account Apparatus, of which the following is a specification, reference being had therein to the accompanying drawing.

10 This invention relates to the subject of credit systems, and has particularly in view a filing cabinet therefor which is made in book form, the leaves of which may be readily removed or added to, and each leaf 15 being provided with a plurality of sales slip holders which readily permit the slips to be removed, yet at the same time assure of the same being held in a conspicuous manner so that they may be inspected.

20 The invention is primarily designed for use in connection with credit systems where duplicate or triplicate sales slips are employed, one or more to be kept within a portable filing cabinet, one to be retained by a 25 customer, and, if three slips are used, the third to be kept by the store and filed away in a ledger.

It will be understood, of course, that in the practical application of the invention to the 30 system, the same is susceptible of changes in details and structural arrangements, but one preferred and practical example thereof is shown in the accompanying drawings, wherein—

35 Figure 1 is a perspective view of the improved filing cabinet, the cover leaves thereof being opened. Fig. 2 is a detail side elevation of the hinge connection between the leaves of the cabinet. Fig. 3 is a view similar to Fig. 2, showing the binding or locking engagement between the hinge connection of the cover and the hinge connection of the leaves.

40 Referring to the accompanying drawings by numerals, 1 and 2 designate, respectively, the covers of the filing cabinet, which is of a book form so that the same may be portable. The cover 1 on its inner face is provided with four corner pockets 3 which receive the corners of an index sheet 4 and 45 preferably also the corresponding corners of a transparent protecting sheet 5 for the alphabetical and numerical index sheet 4. The other cover 2 has a pad or tablet 6 secured thereon, each sheet of which may be 50 provided with the necessary horizontal and

vertical lines for the keeping of accounts. The pad or tablet is so arranged that its sheets may be readily torn off when desired or necessary. 60

The leaves 7 are of duplicate construction and arrangement, and they, as well as the covers may be formed of pasteboard, fiber, or metal. The leaves are provided at their longitudinal edges with protecting strips 8 65 which project on each side of the leaf, and are also provided with a central partition strip 9 which is arranged similar to the side strips, so that each leaf has both sides divided into two longitudinal compartments. 70 As is shown more clearly in Fig. 1, when the leaves are closed, the side strips of each leaf rest upon the side strips of the leaf below, and the central partition strip rests upon the central partition strip below, which arrangement assures of ample space being left between the compartments of each leaf. The strips 8 may be indexed correspondingly with the cover index. 75

The covers at the inner ends of their longitudinal edges are provided with hinge straps 10, the end of each of which is in pivotal engagement with one end of a hinge link 11, said hinge link having its other end provided with an inclined transversely arranged slot 12 for detachable engagement with a pivot stud 13 carried by a strap or plate 14 fastened to the longitudinal edge of the side member of each outer leaf. This plate or strap 14 is located preferably at one 80 edge of the said member or strip, and a duplicate thereof, as designated at 15 is located at the opposite edge of said strip, said plate or strap 15 being in turn, in engagement with a similar plate or strap 16 carried by 85 the next leaf, through the medium of a hinge link 17. This manner of hingedly connecting the several leaves together, and the outer leaves thereof to the cover is continued,—the arrangement being such that 90 each side strip of the leaves has a hinge link connection with the leaf above and the leaf below, and the covers each have a detachable hinge connection with the outer leaves. 95

100 The hinge straps and the hinge links are all provided with rounded ends and are held in binding contact with one another when the cabinet is closed, the contact being a close one, so that the leaves and covers are practically jammed or locked together; sufficiently to withstand ordinary jars or movements without danger of being forced apart. 105

As has been stated before, the leaves are divided into longitudinal compartments on each side, by means of the side strips and the central strip, and to utilize these compartments, a plurality of holding clips are employed for retaining sales slips or the like in position in the compartment so that they may be readily inspected. The holding clips are of duplicate construction, each being formed of a single length of resilient material, such as wire, bent to form side arms 18 and a horizontally connecting front member 19 provided with an intermediate finger grip 20 formed by upwardly, or outwardly bowing the material. The rear ends of the side arms are coiled to form a spiral spring 21, the tension of which is constantly exerted to retain the front connecting member 19 in contact with the bottom of the compartment. These springs project outwardly from their arms, and their outer convolution is passed through the leaf, or bottom of the compartment and into the compartment on the opposite side of the leaf and stapled or otherwise securely fastened therein, as indicated at 22.

The edges of the side strips opposite to the holding clips in each compartment may be supplied with an initial, letter, number, or other distinguishing mark in order to readily identify the slips held by the clips.

It will be seen from the foregoing that by means of the hinge connection between the covers and the leaves, the covers may be readily detached to permit additional leaves to be added to the cabinet, and by the described compartment arrangement of the leaves a large number of slips may be retained in position to be readily inspected. And, also, through the use of the described holding clips, the slips are securely retained in position, but may be quickly removed, or added to when desired.

What I claim as my invention is:—

- 45 1. A portable filing cabinet comprising outer covers, a plurality of leaves hinged together, and a detachable hinge connection between the covers and the outermost leaves.
2. A portable cabinet for sales slips com-

prising covers, a plurality of leaves each 50 having an independent hinge connection with an adjacent leaf, and a detachable hinge connection between each cover and each outermost leaf.

3. A portable filing cabinet, comprising 55 covers each provided with hinge members one end of each of which is provided with a slot, a plurality of leaves each having an independent hinge connection with an adjacent leaf, and pivot lugs carried by the outermost leaves for detachable engagement with the slotted end of the hinge members of the covers.

4. A portable filing cabinet, comprising 60 covers each provided with hinge members the free ends of which are rounded and have transverse slots formed therein, a plurality of leaves, a rounded end link connection between each leaf and an adjacent leaf, and pivot studs carried by each outermost leaf 65 for detachable engagement with the slotted ends of the hinge members of the covers, the links of the leaves being adapted to have binding engagement with each other and with the hinge members of the covers when 70 the cabinet is in a closed position.

5. A filing cabinet comprising a plurality of leaves, hinge members carried by each leaf, a link connection between the hinge members of one leaf and the adjoining leaf 75 covers for said leaves, and a detachable hinge connection between said covers and the hinge members of the outermost leaves.

6. A filing cabinet comprising a plurality of leaves, hinge members carried by each 80 leaf, link connections between the hinge members of one leaf and the adjacent leaf, said links having a binding engagement when the leaves are closed, covers for said leaves, and a detachable hinge connection between said covers and the outermost leaves. 85

In testimony whereof I hereunto affix my signature in presence of two witnesses.

JOHN T. BROOKE.
